CLAIM

The ornamental design for an active platform, as shown and described.

DESCRIPTION

FIG. 1 is a perspective view of an active platform, showing my new design;

FIG. 2 is a left elevational view thereof;

FIG. 3 is a right elevational view thereof;

FIG. 4 is a front view thereof;

FIG. 5 is a rear view thereof;

FIG. 6 is a bottom view thereof; and,

FIG. 7 is a top view thereof.

The broken lines in the drawings are for the purpose of illustrating portions of the active platform, which form no part of the claimed design to be patented.
